UNITED STATES PATENT OFFICE

BENJAMIN WOLHAUPTER, OF NEW ROCHELLE, AND BANCROFT G. BRAINE, OF NEW YORK, N. Y., ASSIGNEES TO THE RAIL JOINT COMPANY, OF NEW YORK, N. Y., A CORPORATION OF NEW YORK.

INSULATED RAIL-JOINT.

1,221,260.

Specification of Letters Patent. Patented Apr. 3, 1917.

Application filed December 23, 1914. Serial No. 878,710.

To all whom it may concern:

Be it known that we, BENJAMIN WOLHAUPTER and BANCROFT G. BRAINE, citizens of the United States, residing, respectively, at New Rochelle, county of Westchester and State of New York, and New York, in the county of New York and State of New York, have invented certain new and useful Improvements in Insulated Rail-Joints, of which the following is a specification.

This invention relates to splice-bar insulation for insulated rail joints, and particularly to that type of sectional insulation including separate pieces of insulation for the head and base portions of the rails and splice bars.

Primarily, the invention has in view an improvement in the structural form and arrangement of the separate pieces or plates of insulation employed in insulated rail joints, whereby the insulating material may be manufactured in standard lots and also utilized in an economical manner with respect to maintenance and renewals.

Accordingly, a distinctive object of the invention is to provide a novel and useful construction which permits the insulation plates to be made in standard lots and kept in stock in quantities for each section of rail. This enables the manufacturer to supply insulation plates out of stock without requiring them to be specially slotted for the bolts, as is ordinarily required for the conventional insulation plates of insulated rail joints.

As is well known, the distance between the joint bolts of a rail joint varies according to different requirements, and in those forms of insulation plates depending upon the bolts to hold them in position against longitudinal and vertical displacement, it is necessary to specially slot the plates for the bolt holes according to the specified distancing of the joint bolts. However, according to the present invention, the joint bolts are not utilized as a means to assist in locking the insulation plates against longitudinal displacement, but means are provided whereby the said plates are interlocked in position by the end post and the usual normal variations in the distancing of joint bolts is disregarded, thereby making it possible to manufacture said plates in quantities, of a standard size, so that the same are readily adaptable to different spacings of bolts. At

the same time, the invention also contemplates a novel construction and arrangement of parts whereby the separate sections or plates of insulation are separately removable or replaceable without disturbing good or unworn pieces of insulation.

With these and other objects in view which will be apparent to those familiar with this art, the invention consists in the novel construction, combination, and arrangement of parts hereinafter more fully described, illustrated, and claimed.

Though susceptible of structural modification and applicable to diverse forms of splice bars, certain preferred and practical embodiments of the invention are illustrated in the accompanying drawings, in which—

Figure 1 is a perspective view of an insulated rail joint, with one joint bar removed to expose the improved sectional splice bar insulation constructed in accordance with the present invention.

Fig. 2 is a skeleton cross sectional view of the complete improved sectional insulation as it appears at the center of the joint, the view showing a bisected elevation of the insulating end post as it appears in the center of the joint to show its interlocking engagement with the web and base sections of the base insulation.

Fig. 3 is a side elevation of a modification of the improved sectional splice bar insulation illustrating a different arrangement of the holding ears and shouldered retaining seats of the interlocked head and base insulation plates.

Similar reference characters designate corresponding parts throughout the several figures of the drawings.

The novel interlocked sectional splice bar insulation is applicable to different kinds of rail joints, and hence to any recognized form of splice, so for illustrative purposes there is shown in Fig. 1 of the drawings a rail joint including the usual rails 1, the splice or joint bar 1 of the continuous type which includes an upright member 2, a foot member 3, and a rail supporting base member 4. The illustrated joint also includes the usual joint bolts 5 and splice bar insulation which essentially comprises an upper insulation plate 6 and a lower insulation plate 7.

The upper and lower insulation plates 6 and 7 are made of ordinary fiber sheets or

any other suitable insulating material, and the upper insulation plate 6 constitutes the rail head insulation and is interposed between the under side of the rail head and the upper edge of the splice bar. Correspondingly, the separate lower insulation plate 8 constitutes the base insulation for the joint and includes a flange section 8 overlying the rail flange and has formed integrally thereto with an upstanding web portion 9 lying next to the web of the rail. The said flange section 8 of the base insulation is also formed integrally at its outer edge with a horizontal inwardly extending base section of insulation 10 which underlies the rail base and forms with the flange section 8 a cuff which completely receives and insulates the rail base flange.

In the embodiment of the invention shown in Figs. 1 and 2 of the drawings, the rail head insulation, consisting of the upper insulation plate underlying the rail head at each side of the rail, is disposed wholly above the top line of the joint bolts, and therefore has no contact or engagement with such bolts that would require any machining of the said upper insulation plate to meet variations in bolt spacing, thereby permitting the said plate to be manufactured in standard size and quantities regardless of bolt spacing. This is provided for by the novel manner in which the upper and lower insulation plates are constructed and interlocked. As plainly shown in Fig. 1 of the drawings, it will be observed that the upper insulation plate 6 not only lies wholly above the line of the bolts, but is also formed at its lower end edges with cut out portions 11, forming shouldered retaining seats which receive the upper shouldered ends 12 of extension holding ears 13. These are extended upwardly from the main web portion of the base insulation plate 8 and project a sufficient distance from the body of the plate so as to extend above the line of the bolts, and thereby interlock with the retaining seats 11 of the upper insulation plate. Furthermore, it will be observed that this construction involves the formation between opposite holding ears 13 of a cut away space 14. This cut away space constitutes a bolt clearance space which is of a length coextensive with or greater than the maximum customary spacing of the bolts extending through one of the rails.

With further reference to the feature of providing a maximum clearance between the joint bolts and the holding ears of the base insulation plate, it will be noted, in the form of construction shown in Figs. 1 and 2, that the said base insulation plate is provided at the central portion thereof with a single or double holding ear 13-13 to meet the situation of separate upper insulation plates 6 being employed for the separate rails.

Under this condition the width or combined width of the single or double holding ear 13-13 at the center of the base insulation plate 8 is shorter than the minimum customary distance between the two center bolts of any form of insulated rail joint now in use.

In order to effectually interlock the separate sections or plates of insulation together, and independently of the joint bolts, the insulating end post 15 between the rail ends, is preferably provided at its side edges with side locking tenons 16 engaging side keeper slots 17 in the web portions of the base insulation and at the bottom with a bottom locking tenon 18 which engages and interlocks with bottom keeper slots or notches 19 formed at the centers of the base sections 10 of the base insulation.

It will thus be seen that the combination of instrumentalities described, including the insulated end post, provide a very effective interlock for the various pieces of insulation to prevent longitudinal displacement thereof, while at the same time permitting such pieces of insulation to be made in standard quantities without having to be machined for different spacings of bolts, and also permitting the various pieces of insulation to be independently removed or replaced as the condition of the joint may require.

The same principles of construction will apply to all applications of the invention as may be exemplified by the modification of Fig. 3 of the drawings. In this modification, the upper insulation plates are illustrated as being provided at their extreme inner ends only with deepened portions forming shouldered retaining seats 20, into which project the single extension holding ears 21 which are formed at the central part of the base insulation and project upwardly through the space between the two center bolts of the joint. In this form of construction cut away bolt clearance spaces 22 are provided above the web portion 9 of the base insulation, said spaces being of greater longitudinal extent than the maximum customary spacing of four-bolt joints. Fig. 3 shows them in use with a six-bolt joint. They can thus be used in joints with six or more bolts, or with abnormal or unusual spacing of the bolts. Also, in the modified construction, the combined width of the central holding ears 21 is less than the least customary spacing between the two central bolts of a joint.

Other modifications and forms of construction may be resorted to, within the scope of the appended claims, without departing from the principle or sacrificing any of the advantages of the invention.

We claim:

1. An insulated rail joint including splice

- bar insulation comprising separate upper and lower insulation plates having a direct interlocking engagement and having complementary portions forming and bounding a bolt clearance space for the bolts in each rail, said clearance space being of an extent to receive a plurality of joint bolts for all normal spacings thereof. 5
2. An insulated rail joint including splice bar insulation comprising separate upper and lower insulation plates having a direct interlocking engagement and having complementary portions forming and bounding a bolt clearance space for the bolts in each rail, said clearance space being of an extent to receive a plurality of joint bolts for all normal spacings thereof, and means independent of the joint bolts for holding the interlocked plates against longitudinal displacement. 10
3. An insulated rail joint including splice bar insulation comprising an upper insulation plate provided adjacent the center of the joint with a retaining seat, and a lower insulation plate having an extension holding ear projecting through the space between the center joint bolts and interlocking with said seat, the said lower plate being cut away at one side of the ear to form a clearance for the joint bolts for all normal spacings thereof. 15
4. An insulated rail joint including splice bar insulation comprising an upper insulation plate provided with oppositely located retaining seats, and a lower insulation plate provided with oppositely arranged extension holding ears disposed at one side of the joint bolts and directly interlocked with the said seats of the upper plate, the lower plate being formed between said ears with a bolt clearance space of an extent to include two or more adjacent joint bolts in each rail. 20
5. An insulated rail joint including splice bar insulation comprising separate upper insulation plates for the separate rails, each provided with a retaining seat, and a lower insulation plate provided with a holding extension projecting through the space between the center bolts of the joint and interlocking with said seats of both of the upper plates. 25
6. An insulated rail joint including splice bar insulation comprising separate upper insulation plates for the separate rails, each provided with a retaining seat, and a lower insulation plate provided with a holding extension projecting through the space between the center bolts of the joint and interlocking with said seats of both of the upper plates, said holding extension being of less width than the normal minimum spacing of the central bolts of a rail joint. 30
7. An insulated rail joint including splice bar insulation comprising separate upper in-
- sulation plates for the separate rails provided at both ends thereof with retaining seats, and a lower insulation plate provided at both ends and at its central portion with holding ear-extensions projecting above the joint bolts and interlocking with the said seats of the upper plates. 70
8. An insulated rail joint including splice bar insulation comprising separate upper insulation plates for the separate rails, a lower insulation plate having a direct interlocking connection with the upper plates, and an insulating end post having an interlocking engagement with only the lower insulation plate. 75
9. An insulated rail joint including splice bar insulation comprising upper insulation plates, a lower insulation plate provided with a central extension interlocking with the upper plates and having a side keeper slot 80 therein, and an insulating end post having an interlocking engagement with said slot. 85
10. An insulated rail joint including splice bar insulation comprising upper insulation plates, a lower insulation plate having an intermediate extension interlocking with the upper plates and a slot in said extension, said lower insulation plate being also provided with a base section formed with a slot therein, and an insulating end post interlocking with both slots of the lower plate of insulation. 90
11. An insulated rail joint including a lower insulation plate for the rail base flanges having a web portion and a base portion, an upper insulation plate interlocking directly with said lower insulation plate, and an end post having a separate interlocking engagement respectively with the web and base sections of the lower insulation plate. 100
12. An insulated rail joint including an insulation plate provided with a web portion having a vertically disposed slot therein and a base section having a horizontally disposed slot therein, and an insulating end post having a side locking tenon engaging said vertically disposed slot, and a bottom locking tenon engaging said horizontally disposed slot. 110
13. An insulated rail joint including separate upper and lower insulation plates having a direct interlocking engagement and also having complementary portions forming a bolt clearance space adaptable to any normal spacing of the track bolts, and an insulating end post having an interlocking engagement with one of the insulation plates. 115
14. An insulated rail joint including upper and lower insulation plates having a direct interlocking engagement and also having complementary portions forming and bounding a bolt clearance space for the bolts at one side of the joint between the rails, said clearance space being of an extent to receive said bolts for any normal spacing 120
- 125
- 130

thereof, and an insulating end post interlocked with one of said plates.

15. An insulated rail joint including upper and lower insulation plates having a direct interlocking engagement and also having complementary portions forming and bounding a bolt clearance space for the bolts at one side of the joint between the rails, said clearance space being of an extent to 10 receive said bolts for any normal spacing

thereof, and an insulating end post interlocking with the lower insulation plate.

In testimony whereof we hereunto affix our signatures in the presence of two witnesses.
